UNITED STATES PATENT OFFICE.

CHARLES ROBERT WRIGHT, OF MACOMB, ILLINOIS, ASSIGNOR TO MACOMB MANUFACTURING COMPANY, OF MACOMB, ILLINOIS, A CORPORATION OF ILLINOIS.

DESIGN FOR A CHAIR OR THE LIKE.

Application filed July 27, 1928. Serial No. 27,605. Term of patent 7 years.

To all whom it may concern:

Be it known that I, CHARLES ROBERT WRIGHT, a citizen of the United States, residing at Macomb, in the county of McDonough and State of Illinois, have invented a new, original, and ornamental Design for Chair or the like, of which the following is a specification, reference being had to the accompanying drawing, forming part thereof, wherein—

Figures 1, 2, and 3 are respectively a front elevation, a side elevation, and a top plan view of a chair showing my new design.

I claim:

The ornamental design for a chair or the like, as shown.

CHARLES ROBERT WRIGHT.
